Primary Examiner—James R. Largen

[57] CLAIM

The ornamental design for a hand-held electric prod, as shown.

DESCRIPTION

FIG. 1 is a perspective view of a hand-held electric prod showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

The dotted lines in FIG. 1 are for illustrative purposes only and form no part of the claimed design.

FIG.1

FIG.2

FIG.3

FIG.4

FIG.5

FIG.6

FIG.7
